(57) **CLAIM**

The ornamental design for a screen protector applicator kit as shown and described.

DESCRIPTION

FIG. 1 is a front, left and bottom perspective view of a screen protector applicator kit showing our new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front, left and bottom perspective view thereof showing the screen protector applicator kit in a state of use; and,

FIG. 10 is further another front, left and bottom perspective view thereof showing the screen protector applicator kit in another state of use.

The broken lines depict portions of the screen protector applicator kit that form no part of the claimed design.

1 Claim, 10 Drawing Sheets
